Application April 3, 1953, Serial No. 346,724

19 Claims. (Cl. 28—28)

This invention relates to the formation of a warp from a plurality of running ends of yarn and is more particularly concerned with the preparation of warp from continuously spun and aftertreated rayon yarns so that a large number of running yarns can be simultaneously subjected to drying and/or further finishing.

In the continuous spinning of rayon yarns one of the problems which is always encountered is the handling of the still running yarns after the wet treatments are finished and before the yarn is collected. Where the aftertreatments are effected on thread-storage, thread-advancing devices, the usual practice has been to pass the yarns to a final thread-storage, thread-advancing device on which they are individually dried. With the advent of more modern aftertreating systems, such as tube spinning, it is not economically feasible to effect drying on thread-storage, thread-advancing devices which have to be spun individually for to do so would, at least somewhat, offset the advantages of the automatic spinning which the newer continuous systems afford. On the other hand, to dry the yarns in warp form involves the inherent difficulty of disposing of the running ends at the beginning of an operating period when the warp is being formed from individually running yarns.

A further complicating factor is plant space. Most of the aftertreating systems require more space between the units for treating a single yarn than the very close spacing which exists between adjacent yarns of a warp. Thus, if the yarns are brought together but continued in the same general direction as that in which they were liquid treated, space is wasted and double-sided machines cannot be used. If they are changed in direction, the problem has been how to do it in a simple and inexpensive way.

It is then an object of the invention to overcome the foregoing difficulties and to provide for the formation of a warp from running ends of yarn however produced and, if desired, to give that warp a change in direction such that plant space may be saved and two-sided machines may be used.

It is contemplated according to this invention to provide for the automatic accommodation of all of the running ends as they are delivered by a spinning machine so that the advantages of automatic spinning-in are retained, labor cost is reduced and the remaining manual steps in warp formation are greatly facilitated.

Other objects and advantages of this invention will be apparent upon consideration of the following detailed description of a preferred embodiment thereof in conjunction with the annexed drawings wherein:

Figure 1 is a perspective view of the finishing side of a tube spinning machine showing a warp forming trough arrangement according to the present invention;

Figure 2 is a fragmentary top plan view of a portion of the warp forming apparatus of the machine of Figure 1 as it appears after spinning-in;

Figure 3 is a view in vertical section of the same fragments of the machine that are shown in Figure 2 but

2

illustrating the yarn receiving trough with yarns entering it as they do during spinning-in;

Figure 4 is a view in plan downstream from but correlated with Figure 2;

Figure 5 is a view in vertical section downstream from but correlated with Figure 3;

Figure 6 is a fragmentary view in cross-section of the machine of Figure 1 looking upstream of the yarn receiving trough;

Figure 7 is a view partially in elevation and partially in section showing a warp guiding comb near the upstream end of the machine;

Figure 8 is a view in section taken on the line 8—8 of Figure 7;

Figure 9 is a view in section taken on the line 9—9 of Figure 7;

Figure 10 is a view in top plan of a warp guiding comb construction of the type used near the upstream end of the machine; and

Figure 11 is a view in top plan of a warp guiding comb construction of the type used near the downstream end of the machine.

In Figure 1, there is shown the right hand side of a two-sided tube spinning machine of the type having one hundred forty-four spinning positions. The illustrated right hand side of the machine comprises a spinning side 10, groups 11 of aftertreating tubes and a finishing and warp forming section 12. The unillustrated side is similarly constituted and for that reason, this description is confined to one side of the machine with the understanding that the machine on the other side of the center catwalk is, in effect, the mirror image of the illustrated apparatus.

The spinning side 10 of the machine of Figure 1 includes an elongated spinning bath 13 which extends for the full length of the machine and which accommodates seventy-two spinnerets. Yarn issuing from each spinneret is led around one of the godets of the pair 14 to a hot water bath 15, back to the other of the godets of the pair 14 and then to the tube group 11 in which aftertreating is effected in accordance with the principles of Griset application Serial No. 122,560, filed October 20, 1949, now Patent No. 2,725,276, issued on November 29, 1955. Yarn issuing from the last aftertreating tube of a group 11 is discharged into the end of a large diameter drain tube 17 from which it is discharged into an elongated V trough 16 extending for the full length of the machine on the finishing side thereof. The enlarged tubes 17 are shown to small scale in Figure 1. A finishing solution flows in the trough 16 from right to left, as the trough appears in Figure 1, so that the yarns discharged from the tube 17 fall into a flowing stream of finishing liquid and are carried downstream as a group later to be formed into a warp and dried by steps and apparatus hereinafter described.

From a study of said Griset Patent No. 2,725,276, it can be appreciated that the velocity at which the yarn is propelled through the treating tubes is, *inter alia*, a function of the length and diameter of those tubes and the speed at which the propelling and treating liquid is introduced. Thus, for the sake of easy maintenance of uniformity in yarn propulsion rate and treatment, the last tube of each group 11 ought to be of the same length as the others. This means that the last tube of each group cannot vary appreciably in length. On the other hand, it will be readily understood that in order to form a warp sheet out of the yarn issuing from all the tubes, it is desirable that the last tube of each group near the upper end of the machine, where the warp sheet is relatively narrow, be progressively longer. Conversely, near the lower end of the machine, where the warp sheet is broader, the last tube in each group needs to be successively

shorter. The problem is solved by having the last tube of each group 11 discharge into a sloping tube 17 of very large cross section in comparison to an aftertreating tube. Thus, the tube 17, which has no pressure-velocity effect on propulsion rate in the group 11 and yet serves as a duct to deliver the treating liquid and the yarn from the last aftertreating tube to the trough 16, may be of varying length depending on its position along the length of the machine.

The shape and position of the trough 16 can best be understood by concurrent reference to Figures 2 to 6, inclusive. It will be noted that the finishing side or warp forming section 12 of the machine includes a group of spaced vertical standards 18 and, in a row parallel to them, another group of vertical standards 19. These standards are positioned opposite one another six spinning positions apart. The trough 16 is supported at spaced points along the machine from standards 18 and 19 in a manner which can best be understood by reference to Figure 6. The trough is made in the form of a V with one vertical side and one sloping side. The vertical side lies in the plane of the standards 19, and the sloping side slopes upwardly toward the standards 18 and is supported by frame elements 18a extending from frame 18 to a rigid angle piece 16a affixed to the trough edge. The trough is very shallow and very narrow at its upstream end as can be appreciated from Figures 2, 3 and 6. It extends the full width of the space between standards 18 and 19 at the downstream end. Because of the fact that the bottom of the trough at the upstream end of the machine is higher than the bottom thereof at the downstream end thereof, it is apparent that a liquid introduced into the trough will flow downwardly within the trough to its lowest point. The lower end of the trough 16 is shown in Figure 5, and it discharges into a chute 20 which in turn discharges into a finishing liquid return box 21 (see Figure 4) positioned below warp draw-off rollers 22 and 23.

Finishing liquid is introduced into the upstream end of the trough 16 through a spout 24, see Figure 3, supplied from a pipe 25 through a valve 26. The liquid flows down the trough 16, falls into the box at 21 and is recirculated by means, not shown, to pipe 25. The last tube of each tube group in the aftertreating section 11 is also supplied with finishing liquid, see for example, the single one of these tubes which appears in Figure 6 at 27. That finishing liquid, with the yarn, enters a straight tube 17 of enlarged diameter which in turn discharges into the trough 16. Consequently, the trough derives finishing liquid not only from the spout at 24 but also from the various tubes 17 which discharge both the yarn and the treating liquid therein.

Since the treating liquid is flowing down hill from the upstream to the downstream end of the trough, it is apparent that yarn discharged into the stream will be carried thereby to the downstream end of the machine. This is illustrated in Figures 3 and 5. The slope of the trough is calculated to be enough to make the liquid flow therein at a speed in excess of the speed of propulsion of the yarns through spinning and aftertreating. The yarns do not tangle very much in their movement along trough 16 due to the fact that the tubes 17 are of progressively decreasing length from the upstream to the downstream end of the machine so that each tube terminates just over the inside sloping edge of the trough. This is clearly shown in Figure 6 where the upstream tube 17 extends to a position above the nearer edge of the narrow part of the trough while the downstream tube 17 assumes a like position with respect to the sloping edge of the wide downstream portion of the trough. The large number of intermediate tubes 17 which actually exist between the two tubes shown in Figure 6 have been omitted for clarity of illustration, but a clear concept of their gradations in length can be had by reference to Figure 2.

Once the yarn is spun-in and is issuing from the various tubes 17, as shown in Figures 3 and 5, it will be washed downstream through the chute 20 and into the box 75

21. The box has a screen 28 at its bottom so that the finishing liquid can go through while the yarn will not. When all of the positions are spinning properly, the operator combs them out in combs extending across the trough and delivers the combed warp through draw-off rollers to drying rollers. The point to be emphasized in respect to combing is apparent from Figure 2. All of the aftertreating tubes of the groups 11 terminate in the same plane which is marked as plane a—a of Figure 2. The outer edge of the trough 16 lies in plane b—b of Figure 2. The nearer edge of the trough 16 and the plane of the ends of the tubes 17 are both convergent toward the plane a—a, in the downstream direction, and divergent from the plane b—b in the same way. Thus, the yarns 10 are automatically offset in the trough 16 as they fall into it. The operator combs out the yarns by inserting a comb after every sixth spinning position beginning with the short comb 29 of Figures 2 and 10 and ending with the long comb 30 shown in Figures 4 and 11. The combs, 15 such as combs 29 and 30, are held in brackets so that the operator may raise manually the bundle of yarns running in the bottom of the trough, put the combs in position and then drop the yarns into the combs to align the warp.

26 Just how the combs are mounted and maintained to accomplish the foregoing purpose will be apparent from reference to Figures 7 to 11, inclusive. The brackets which support the combs are affixed respectively to standards 18 and 19. The standards are disposed in mutually 30 spaced relation in parallel planes and it is therefore evident that a combing bar or tube extending between these standards will be much too long at the upstream end of the machine. This is taken care of by making the combs in groups of six beginning at one end of a supporting tube 35 or bar. The standards 19 are provided with U-channel brackets 31 bolted to the standards by bolts 32. The standards 18 are similarly equipped with oppositely facing brackets 33 held by bolts 34. A tube, such as tube 35 of Figure 7, is provided with flats 36 at opposite sides 40 at both ends to make a nonrotatable fit in the brackets 31 and 33. A pin 37 is passed through the tube 35 and the bracket 31 to lock tube 35 against axial slippage. The tube 35 has seven holes drilled through it to accommodate seven comb teeth 38. These teeth define the side walls of a comb for six yarns while the bottom or bearing surface of the comb is defined by a tube 39 overlying a rod 40. The rod 40 is threaded at both ends and fitted with a pair of nuts at each end, one of which shows at 41 in Figure 8. Brackets 42 and 43 are held by screws from the tube 35 and these brackets encase the nuts at 45 the ends of the rod 40 whereby the rod 40 is held in fixed position relative to the tube 35 and the tube 39 is held tangent to the teeth 38.

Although all of the comb bars or tubes are of the same length as tube 35, as shown in Figures 7 to 10, inclusive, the number of teeth varies with the position of the comb. This is apparent from Figure 11 where there is shown the last comb 30 in the downstream direction. This comb is like the comb at 29 except that the teeth are suitable in number for accommodation of seventy-two yarns and the tubes which define the bottom of the combs are cumulatively of enough length to accommodate seventy-two yarns. In Figure 11 brackets 44 are supported from a tube 45, the brackets corresponding exactly in structure and function to the brackets 42 and 43 of Figure 7. The brackets support a rod 46 which is surrounded by twelve tubes 47 similar in structure and function to the single tube 39 of Figure 10.

The comb structure intermediate the upstream comb 29 and the extreme downstream comb 30 is like that shown in Figures 7 to 11, inclusive, except that the teeth increase in the downstream direction of comb position in increments of six. All of the comb bars are like the tube 35 in structure except for the provision of additional teeth and hence all are readily removable from the re-

5

spective supporting brackets. In threading up the machine the operator begins at the upstream end and raises the bundle of yarns out of the trough. This bundle, at the position of the upstream comb, is comprised of only six yarns. These six yarns are lifted above the level of the brackets 31 and 33, and tube 35 is slipped under them to position. After the comb is in place, the operator drops each yarn between a pair of teeth so that the yarns assume the position shown in Figures 2 and 7. At this stage six ends are combed out and sixty-six ends are not. The operator then takes the next comb downstream, raises the six combed yarns and the uncombed bundle of six to a position above the brackets, inserts the comb and puts the yarns between the comb teeth. This is repeated until the entire machine is threaded and the yarns are running as a continuous warp, as shown in Figures 2 and 4. All the while the running ends of yarn have been drawn off from the trough from the rollers 22 and 23. When the combed part of the warp reaches those rollers, the operator can cut off the waste and lead the warp to drying rollers, such as the bank 48 shown in Figure 1 and from there to a take-up via additional draw-off rollers 49.

What is claimed is:

1. The method of directing and grouping a number of aftertreated individual yarns that are propelled in generally parallel paths to separate points of discharge that comprises flowing a stream of liquid intersecting the points of discharge at an angle to the paths, discharging said yarns onto said stream, supporting and propelling the yarns by said stream to a zone beyond the last discharge point and drawing off the resulting body of yarns at said zone.

2. The method of forming a warp from a group of aftertreated individual yarns that are propelled in generally parallel paths to separate points of discharge that comprises flowing a stream of liquid intersecting the points of discharge at an angle to the paths, discharging said yarns onto said stream, supporting and propelling the yarns by the stream to a zone beyond the last discharge point, drawing off the resulting body of yarns at said zone and thereafter separating and individually guiding the component yarns between the discharge points and the zone.

3. The method of forming a warp from a group of aftertreated individual yarns running in generally parallel paths to separate points of discharge that comprises flowing a stream of liquid intersecting the points of discharge at an angle to the paths, discharging said yarns onto said stream, supporting and propelling the yarns by the stream to an end thereof, drawing off the resulting body of yarns and thereafter separating the yarns from mutual contact between the drawing-off point and the points of discharge and individually guiding the yarns in paths parallel to and above the stream.

4. The method of forming a warp from a group of aftertreated individual yarns running in generally parallel paths to separate points of discharge that comprises flowing a stream of liquid intersecting the points of discharge at an angle to the paths, discharging said yarns onto said stream, supporting and propelling the yarns by the stream to an end thereof, drawing off the resulting body of yarns, thereafter separating the yarns from mutual contact between the zone of drawing off and the points of discharge and drying the resulting warp on the other side of the drawing off zone from the stream.

5. The method of forming a warp from a group of aftertreated individual yarns that are propelled in generally parallel paths to separate points of discharge that comprises flowing a stream of liquid intersecting the points of discharge at an angle to the paths, discharging said yarns onto said stream, supporting and propelling the yarns by the stream to a zone beyond the last discharge point, drawing off the resulting body of yarns at said zone and at a second zone therebeyond, separat-

ing and individually guiding the component yarns between the discharge points and the first draw-off zone, and applying heat to the resulting warp between the first and second draw-off zones.

6. The method of forming a warp from a group of aftertreated individual yarns that are propelled in generally parallel paths to separate points of discharge that comprises flowing a stream of liquid intersecting the points of discharge at an angle to the paths, discharging said yarns onto said stream, supporting and propelling the yarns by the stream to a zone beyond the last discharge point, drawing off the resulting body of yarns at said zone and at a second zone therebeyond, separating and individually guiding the component yarns between the discharge points and the first draw-off zone to form a warp overlying the stream and running to the first draw-off zone, and drying the resulting warp between the first and second draw-off zones.

7. The method of forming a warp from a group of aftertreated individual yarns that are propelled in generally parallel paths to separate points of discharge that comprises flowing at a rate greater than the rate of yarn propulsion a stream of liquid intersecting the points of discharge at an angle to the paths, discharging said yarns and their propelling liquid onto said stream, supporting and propelling the yarns by the stream to a zone beyond the last discharge point, drawing off the resulting body of yarns at said zone and thereafter separating and individually guiding the component yarns between the discharge points and the zone.

8. The method of directing and grouping a number of aftertreated individual yarns that are propelled in generally parallel paths to separate points of discharge while associated with a treating liquid, that comprises flowing a stream of liquid intersecting said points of discharge at an angle to the paths, discharging said yarns and the associated treating liquid into said stream, supporting and propelling the yarns by said stream to a zone beyond the last discharge point and drawing off the resulting body of yarns at said zone.

9. The method of directing and grouping a number of aftertreated individual yarns that are propelled by a treating liquid in a treatment zone that comprises guiding the treating liquid and yarn emerging from the treatment zone in parallel paths to separate points of discharge, gravity flowing a stream of said treating liquid intersecting said points of discharge at an angle to the paths, discharging said yarns and the treating liquid into said stream, propelling the yarns by said stream to a zone downstream of the last discharge point, drawing off the resulting body of yarns and recovering the treating liquid of the stream in said zone and recycling at least some of said treating liquid to said treatment zone.

10. The method of directing and grouping a number of aftertreated individual yarns that are propelled in generally parallel paths to separate point lying in a first plane, individually propelling each yarn in the same general direction beyond said points to discharge points all lying in a second plane defining with said first plane an acute angle, flowing a stream substantially at right angles to said paths and in the direction of convergence of said first and second planes said stream intersecting on one side the points of discharge and on the other side being parallel to said first plane discharging said yarns into said stream whereby the yarns are laterally spaced as they discharge into the liquid and may be conveniently combed into a warp.

11. Apparatus for the formation of warp from a plurality of running ends of yarn that comprises a plurality of units each defining a yarn path, an elongated trough below but with its long axis intersecting the plane of the ends of said yarn paths, means to supply a yarn propelling liquid to said trough, and draw-off means downstream of said trough beyond the last of said yarn path ends.

12. Apparatus for the formation of warp from a plu-

75

rality of running ends of yarn that comprise a plurality of units each defining a yarn path, an elongated trough below but with its long axis intersecting the plane of the ends of said yarn paths, draw-off means downstream of said trough beyond the last of said yarn path ends, means to supply a propelling liquid to said trough and means to cause the liquid to flow in a direction toward said draw-off means.

13. Apparatus for the formation of warp from a plurality of running ends of yarn that comprises a plurality of tubular liquid treatment units each having a yarn discharge end, an elongated trough below but with its long axis intersecting the plane of said discharge ends, means to flow a liquid through said trough, draw-off rollers downstream of said trough beyond the last of said discharge ends, a plurality of removable combs extending transversely of said trough at spaced points therealong and drying means beyond said draw-off rollers in the direction of yarn travel.

14. Apparatus for the formation of warp from a plurality of running ends of yarn that comprises a plurality of tubular liquid treatment units each having a yarn discharge end, an elongated trough below but with its long axis intersecting the plane of said discharge ends, means to supply a propelling liquid to said trough, draw-off rollers downstream of said trough beyond the last discharge ends and a plurality of removable combs extending transversely of said trough at spaced points therealong.

15. Apparatus for the formation of warp from a plurality of running ends that comprises a plurality of units defining substantially parallel yarn paths terminating in a common plane, a trough having one side parallel to said plane and the other at right angles to said yarn paths, said trough underlying the terminii of said yarn paths and sloping downwardly in the direction of the divergence of its sides and means to supply a propelling liquid to said trough.

16. Apparatus for the formation of warp from a plurality of running ends that comprises a plurality of units defining substantially parallel yarn paths terminating in a common plane, a trough having one side parallel to said plane and the other at right angles to said yarn paths, said trough underlying the terminii of said yarn

paths and sloping downwardly in the direction of the divergence of its sides, means to supply a propelling liquid to said trough and a plurality of removable combs extending across said trough at spaced points therealong.

17. Apparatus for the formation of warp from a plurality of running ends that comprises a plurality of units defining substantially parallel yarn paths terminating in a common plane, a trough having one side parallel to said plane and the other at right angles to said yarn paths, said trough underlying the terminii of said yarn paths and sloping downwardly in the direction of the divergence of its sides, means to supply a propelling liquid to said trough and draw-off means at the downstream end of the said trough.

18. A comb assembly for guiding warp of progressively increasing numbers of component yarns that comprises a plurality of mutually facing brackets on opposite sides of the intended warp path, a bar removably supported in each bracket, each bar having progressively more teeth

20 in the direction of increase in the number of component yarns of the warp, a trough underlying the toothed portion of all of the bars, and means to cause liquid to flow in said trough in the direction of the combs of greater numbers of teeth.

19. A comb assembly for guiding a warp of yarn along an intended path overlying a trough, said comb assembly comprising a supporting bar having teeth projecting therefrom, means for quick detachably mounting said supporting bar in a predetermined position with respect

30 to the trough, means defining a round yarn bearing surface and means supported by said bar for removably holding said bearing surface defining means in tangent relation to said teeth.
